(57) CLAIM

The ornamental design for a device for applying nail decals, as shown and described.

DESCRIPTION

FIG. 1 is a top plan view of a device for applying nail decals showing a first embodiment of my new design;

FIG. 2 is a bottom plan view thereof;

FIG. 3 is a front side elevation view thereof;

FIG. 4 is a right side elevation view thereof;

FIG. 5 is a left side elevation view thereof;

FIG. 6 is a top plan view of a second embodiment of the device shown in FIG. 1;

FIG. 7 is a bottom plan view thereof;

FIG. 8 is a front side elevation view thereof;

FIG. 9 is a right side elevation view thereof;

FIG. 10 is a left side elevation view thereof;

FIG. 11 is a top plan view of a third embodiment of the device shown in FIG. 1;

FIG. 12 is a bottom plan view thereof;

FIG. 13 is a front side elevation view thereof;

FIG. 14 is a right side elevation view thereof;

FIG. 15 is a left side elevation view thereof;

FIG. 16 is a top plan view of a fourth embodiment of the device shown in FIG. 1;

FIG. 17 is a bottom plan view thereof;

FIG. 18 is a front side elevation view thereof;

FIG. 19 is a right side elevation view thereof; and,

FIG. 20 is a left side elevation view thereof.

The device for applying nail decals is shown with a symbolic break, the appearance of any portion between the break form no part of the claimed design.

The broken lines in the figures are for the purpose of illustrating portions of the device for applying nail decals, which form no part of the claimed design.

1 Claim, 20 Drawing Sheets
